UNITED STATES PATENT OFFICE

96,722

DESIGN FOR A CUP

Vincent Broomhall and Herbert A. Smith, East Liverpool, Ohio, assignors to The Salem China Company, Salem, Ohio, a corporation

Application March 4, 1935, Serial No. 55,728

Term of patent 3½ years

To all whom it may concern:

Be it known that we, Vincent Broomhall and Herbert A. Smith, citizens of the United States, residing at East Liverpool, county of Columbiana, and State of Ohio, have invented a new, original, and ornamental Design for Cups, of which the following is a specification, reference being made to the accompanying drawing, forming a part thereof.

Fig. 2 is a side elevational view of same; and
Fig. 3 is a bottom plan view of same.

The sides of the cup and also the handle are of a streamline or tapering shape and this streamline shape is the essential feature of the design.

What we claim is:—

The ornamental design for a cup, as shown and described.

VINCENT BROOMHALL.
HERBERT A. SMITH.
